UNITED STATES PATENT OFFICE.

CHARLES M. HORTON, OF ELIZABETH, NEW JERSEY, ASSIGNOR TO THE SINGER
MANUFACTURING COMPANY, A CORPORATION OF NEW JERSEY.

FOLDER FOR HEAVY FABRICS.

1,118,284.

Specification of Letters Patent.

Patented Nov. 24, 1914.

Application filed May 23, 1913. Serial No. 769,383.

To all whom it may concern:

Be it known that I, CHARLES M. HORTON, a citizen of the United States, residing at Elizabeth, in the county of Union and State 5 of New Jersey, have invented certain new and useful Improvements in Folders for Heavy Fabrics, of which the following is a specification, reference being had therein to the accompanying drawings.

10 This invention relates particularly to an improvement in folding devices adapted to fold heavy fabric strips and to present the folded structure to the stitch-forming mechanism of a sewing machine in the production 15 of canvas belts and the like.

In its preferred embodiment the device consists of a series of spaced folding members formed of narrow metal strips bent to the desired shape, the first members of the 20 series being adapted to partially fold a fabric strip while maintaining its walls in spaced relation and the final member of the series being adapted to draw together the walls of said strip to complete the folding 25 operation. Said folding members are connected and held in register with each other by means of connecting rods which pass through brackets secured to the outer face of each member, the arrangement being such 30 that the members may be given a limited relative adjustment upon said rods. The folding members are shaped to bend a fabric strip from each edge simultaneously toward its center at successively increasing degrees, 35 each member comprising segmental center-guide portions and segmental edge-guide portions, the guide portions of successive members decreasing in segmental area to successively increase the degree of fold.

40 One member carries a tongue, provided at its end with edge stops, which is adapted to guide the edges of the fabric strip to a point in proximity to the center thereof and to hold said edges in alinement. The final 45 member of the series is shaped to impart a fold centrally of the strip and at points intermediate its center and each inturned edge. The device produces a folded structure formed of four superimposed plies 50 lying in the same plane, the edges of the strip being inturned, alined and abutting one fold. The device also comprises means for folding two fabric strips simultaneously to form a six-ply structure, the second strip 55 being half the width of the first strip.

Such construction includes means for centering the second strip with respect to the first strip before the final folding operation, which operation draws together the walls of each strip to fold the same at the center 60 thereof, and to fold the first strip at points intermediate its center and each edge, said edges abutting the second strip at its central fold.

In the drawings, Figure 1 is a perspective 65 view of the folding device. Fig. 2 is a perspective view, partly in section, of the forward members of the device as applied to a Singer belt sewing machine. Fig. 3 is a transverse section through the bed-plate, 70 work-guide and guide-rod of a Singer belt sewing machine, showing the position of the folding device when applied thereto. Figs. 4, 5, 6, 7, 8 and 9 are end views of the folding members, showing in section the position 75 of two fabric strips during the successive folding operations.

In the present embodiment of the invention, six folding members are employed, being formed of narrow metal strips bent to 80 the desired shape. The outer face of each member at the center and sides thereof is provided with brackets 1, adapted to receive connecting rods 2, the said members being secured against movement upon said rods by 85 means of set-screws 3, which permit a limited relative adjustment between the same. Each member, with the exception of the final folding member, is formed with a segmental center-guide portion 4, and with segmental edge-guide portions 5, the guide portions of the successive members decreasing in segmental area to successively increase the degree of fold. The member A is provided 90 at each end with a bracket-seat 6 formed with an opening through which passes rod 7, said bracket-seat being confined between nuts 8 secured upon each end of said rod. By the means just described the ends of member A may be given a slight adjustment 95 toward or from each other, to increase or decrease the degree of fold imparted by such member, the rigidity of member A being maintained throughout such adjustment.

Folding member B is provided in the present instance with edge-stops 9 carried by collars 10 which are adjustable upon the edge-guide portions 5 of said member, said collars being secured in adjusted position 110

upon the said member by set-screws. The function of edge-stops 9 is to center the fabric strip *a* with respect to its line of ultimate central fold. Member B also is 5 provided with auxiliary guides 11, which are used in the production of a six-ply structure. Each auxiliary guide consists of a metal bar connected to the outer end of member B and bent toward the inner face 10 thereof, each being provided in proximity to the latter, with a curved guide portion 12 upon which is adjustably secured an edge-guide 13 which is closed at one end to afford a stop for the strip. Each edge-guide 15 13 is provided with a collar, carrying a set-screw to secure the said guide in adjusted position. The auxiliary guide serves to properly position a secondary fabric strip *b* with respect to the primary strip, during 20 the formation of a six-ply structure. Said auxiliary guide may be carried by member B or a succeeding member, as desired.

The member C is adapted to receive the fabric strip or strips delivered by member 25 B and to increase the degree of fold imparted by member B, as will be understood without further explanation.

In member D the edge-guide portions 30 5 are formed separately from the center-guide portion 4 of the member, the ends of the latter extending in a horizontal plane beyond the edge-guide portions, where they are rigidly held by a connecting rod 14. Each edge-guide portion 5 of member D is 35 connected to a bent arm 5^x carried by collar 15, which is adjustably secured upon one of the horizontal arms of the center-guide portion 4. In member D the edge-guide portions may be moved bodily upon the center-guide portion to decrease or increase the 40 degree of fold.

Member E is formed substantially similar to member D, being adapted, of course, to increase the degree of fold. Member E is 45 provided with an edge controlling tongue, which serves to guide the edges of the strip to a point in proximity to the center thereof, and to so control said edges that the same, when delivered to the final folding 50 member F, are maintained in alinement. In the present instance, the horizontally extending arms 16 of member E are connected at their ends by a rigid bar 17, midway of which is secured, by means of brackets 18, 55 the controlling tongue 19, at the end of which is formed, above and below the body of the tongue, seats or stops 20 for the edges of the strip. Such construction enables the production of a folded structure in which 60 the inturned edges of the strip, abut the central fold in perfect alinement—a result necessary in the production of a fabric belt to avoid the formation of a "soft edge", which would permit the belt to stretch at 65 such point thereby causing the same to shift

laterally on the pulley and finally to leave it. Member E, like member D, is provided with separately formed edge-guide portions, which are adjustable upon the horizontally extending arms 16 of such member. 70

The fabric strip passes from member E to member F, which latter member imparts the final fold. Member F in its action is similar to a drawing die, its function being to draw together the walls of the partially 75 folded strip from the position shown in Fig. 8 to the position shown in Fig. 9. Such member is formed of a single U-shaped metal strip 21 connected at its ends by a bracket 22. Said member is adjustable to 80 various widths of fabric by means of edge guiding stop 23 which slides upon one arm of the member and is secured in adjusted position thereon by a set-screw.

In the drawings the folding device is 85 illustrated as engaging two fabric strips in the formation of a six-ply folded structure. When one strip only is to be folded, a filling plate or the like may be connected to the inner face of member F to compensate for 90 the decreased thickness of the material to be operated upon by said member, as will be understood without further explanation.

By means of the above construction a strip or strips of heavy canvas or the like may be 95 accurately folded at any requisite speed. The folding device may be connected to a sewing machine to deliver the folded structure to the stitch-forming mechanism, by any suitable means. In the present instance, referring to Fig. 2, the device is provided with a bracket-support 24, carrying a split collar 25 adapted to be clamped upon a member of the sewing machine, in this instance guide-rod 26. The folding device is 100 held upon the bracket 24 by means of clamp 27 which engages one of the connecting rods 2 and clamps the same between the face of the clamp and the face of the bracket-arm, by means of clamp-screw 28. In Fig. 2 the 110 folding device is shown in position to deliver a folded structure to the stitch-forming mechanism of a sewing machine through the intermediary of an adjustable work-guide G, which forms no part of my present invention and which does not require detailed description. The folded structure may be delivered to the stitch-forming mechanism of a sewing machine through the intermediary 115 of any suitable work-guide, or directly, 120 as desired.

Having thus set forth the nature of the invention, what I claim herein is:—

1. The folder comprising a series of metal strips formed with substantially segmental 125 center portions and inwardly turned end portions, the degree of curvature increasing in successive strips toward the delivery end of the folder, means carried by one of said strips adapted to receive and maintain the 130

- edges of the material in alinement at the center thereof, and means including a plurality of connecting rods for holding said strips in spaced relation to each other.
- 5 2. The folder comprising a series of metal strips formed with substantially segmental center portions and inwardly turned end portions, the degree of curvature increasing in successive strips toward the delivery end of the folder, means carried by one of said strips adapted to receive and maintain the edges of the material in alinement at the center thereof, means including a plurality of connecting rods for holding said strips 10 in spaced relation to each other, and means whereby the spacing of said strips may be varied.
- 15 3. The folder comprising a series of metal strips formed with substantially segmental center portions and inwardly turned end portions, the degree of curvature increasing in successive strips toward the delivery end of the folder, means carried by one of said strips adapted to receive and maintain the 20 edges of the material in alinement at the center thereof, adjustable edge-guides carried by said strips to accommodate material of various widths, and means for holding said strips in spaced relation to each other.
- 25 4. The folder comprising a series of metal strips formed with substantially segmental center portions and inwardly turned end portions, the degree of curvature increasing in successive strips toward the delivery end 30 of the folder, a guide tongue carried by one of said strips and adapted to lead the edges of the material to the center line thereof, a plurality of connecting rods for holding said strips in spaced relation to each other, and 35 a member carried at the delivery end of the folder having opposed flat faces and adapted to draw together the spaced walls of the material to fold the latter at its center and at points intermediate its center and its 40 turned edges.
- 45 5. The folder comprising a series of metal strips formed with substantially segmental center portions and inwardly turned end portions, the degree of curvature increasing 50 in successive strips toward the delivery end
- of the folder, means including a plurality of connecting rods for holding said strips in spaced relation to each other, a tongue carried by the folder and having at its end on opposite faces two substantially U-shaped seats adapted to receive and aline the in-turned edges of the material, and a member carried at the delivery end of the folder adapted to compress the walls of said partially folded material. 55
- 60 6. In a folding device, in combination, a series of metal folding members formed with substantially segmental center portions and inwardly turned end portions, the degree of curvature increasing in successive members 65 toward the delivery end of the folder, means for maintaining said members in spaced relation to each other, stop devices for the edges of a primary fabric strip being acted upon by the folder, and means including adjustable edge-guides for receiving and centering a secondary fabric strip with respect to the primary strip. 70
- 75 7. In a folding device, in combination, a series of spaced folding-members comprising segmental center-guide portions adapted to bend a fabric strip on a line extending longitudinally and centrally thereof, and segmental edge-guide portions adapted to in-turn each side edge of said strip, the guide portions of successive members decreasing in segmental area to successively increase the degree of fold, a tongue carried by one member to guide the side edges of said strip to a point in proximity to the center thereof and 80 to hold the said edges in alinement, means adapted to draw together the walls of said partially folded strip to impart a final fold centrally thereof and at points intermediate the center and each inturned side edge, and 85 connecting means serving to hold said members in register with each other. 90

In testimony whereof, I have signed my name to this specification, in the presence of two subscribing witnesses.

CHARLES M. HORTON.
